(57) **CLAIM**

The ornamental design for a hula hoop module, as shown and described.

DESCRIPTION

FIG. 1 is a perspective view of a hula hoop module, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left perspective view thereof;

FIG. 7 is a right perspective view thereof;

FIG. 8 is a cross-sectional view as viewed along the line A—A of FIG. 2; FIG. 8 is for illustrative purposes only and forms no part of the claimed design; and,

FIG. 9 is a top plan view thereof, the additional modules forming the completed hoop are shown in broken lines for illustrative purposes only and form no part of the claimed design.
